LLP**CLAIM**

The ornamental design for a bulk bag, as shown and described.

DESCRIPTION

FIG. 1 is a front perspective view of an ornamental design for a bulk bag;

FIG. 2 is a top view of the ornamental design for the bulk bag illustrated in FIG. 1;

FIG. 3 is a front view of the ornamental design for the bulk bag illustrated in FIG. 1; and,

FIG. 4 is a side view of the ornamental design for the bulk bag illustrated in FIG. 1.

The portions of the packaging bags and sachets in broken lines form no part of the claimed design.
